(57) **CLAIM**

The ornamental design for a display screen with graphical user interface for auscultation points, as shown and described.

DESCRIPTION

FIG. 1 is a front elevational view of an ornamental design for a display screen with graphical user interface for auscultation points, in accordance with a first embodiment; and, FIG. 2 is a front elevational view of an ornamental design for a display screen with graphical user interface for auscultation points, in accordance with a second embodiment.

The broken line showing of a display screen, text, and numerals in FIGS. 1-2 is for the purpose of illustrating environment and forms no part of the claimed design.

1 Claim, 2 Drawing Sheets
